UNITED STATES PATENT OFFICE

WAYNE FARRIS, OF WABASH, INDIANA

CIGAR AND CIGARETTE HOLDER

Application filed December 31, 1928. Serial No. 329,401.

This invention appertains to tobacco users' appliances and more particularly to an improved cigar and cigarette holder.

One of the primary objects of the invention is to provide a cigar or cigarette holder in which the butt of the cigar or cigarette can be readily ejected therefrom without difficulty on the part of the user and without the necessity of the user handling the butt.

10 Another important object of the invention is to provide a cigar or cigarette holder embodying a stem having slidably associated therewith a holder portion proper for receiving the cigar or cigarette, spring means being provided for normally holding the holder portion proper in an extended position for receiving the cigar or cigarette, the butt of the cigar or cigarette being automatically ejected from the holder upon movement of 15 the stem and holder portions relative to one another.

A further object of the invention is to provide a substantially conical shaped coil spring with the smaller convulsions of the spring arranged innermost, the spring forming a graduated means for receiving cigars and cigarettes of different diameters.

A further object of the invention is to provide a cigar or a cigarette holder for automatically ejecting the butts thereof including a stem portion and a holder portion proper movable relative to one another with spring means for holding the parts in normal cigar or cigarette receiving position, the spring also functioning to hold the parts in an assembled position, the parts being so arranged that upon removal of the spring, the said parts can be disassembled.

40 A still further object of the invention is to provide an improved cigar and cigarette holder of the above character, which will be durable and efficient in use, one that will be simple and easy to manufacture, and one which can be placed upon the market at a reasonable cost.

With these and other objects in view, the invention consists in the novel construction, arrangement and formation of parts, as will 45 be hereinafter more specifically described,

claimed, and illustrated in the accompanying drawing, in which drawing:

Figure 1 is a side elevation of my improved cigar or cigarette holder showing a cigarette positioned therein.

55 Figure 2 is a longitudinal section through the same.

Figure 3 is a view similar to Figure 1 with the cigar or cigarette holding portion proper in its retracted position for ejecting a cigar 60 or cigarette butt, a cigarette butt being shown in dotted lines.

Figure 4 is a front elevation of the improved holder.

Figure 5 is a transverse section through 65 the holder taken on the line 5-5 of Figure 2, looking in the direction of the arrow, and

Figure 6 is a similar section taken on the line 6-6 of Figure 2, looking in the direction 70 of the arrow.

75 Referring to the drawing in detail, wherein similar reference characters designate corresponding parts throughout the several views, the letter A generally indicates my improved cigar or cigarette holder, which comprises a longitudinally extending bit or stem portion 10. This bit or stem portion 10 can be made from any desired material such as bakelite, hard rubber or the like and is gradually tapered toward the rear end thereof and suitably shaped to provide a mouth piece 11. The forward end of the stem or bit is enlarged to provide an annular flange 12 or ring which defines a stop shoulder 13 for a purpose, which will be later described. This stem or bit is provided with a longitudinally extending bore 14 for the passage of the smoke.

80 In accordance with this invention I provide a body portion 15, which forms the 90 holder proper for the cigar or cigarette and this body portion can also be formed from any desired material and is in the nature of a sleeve or cylinder and the body gradually tapers toward its rear end. The opposite ends of the body is provided with internal shoulders or rings 16 and 17. When the body 95 is in its normal extended position on the stem or bit 10 the shoulder or ring 16 abuts the stop shoulder 13. At this point it is to 100

be noted that the interior diameter of the forward stop shoulder or ring is greater than the shoulder or flange 12 on the stem whereby the body can be slipped off of the stem rearward over the said shoulder or flange 12. Also the mouth-piece 11 is of less diameter than both the shoulders 16 and 17, whereby the body can be slipped over said mouthpiece. This allows the assembling of 10 the parts relative to one another.

The cylindrical body 15 forms a housing for the reception of an expansion coil spring 18, which can be of a comparatively light nature. The convulsions of the expansion coil spring grow less in diameter toward the inner end thereof and the convulsions of the spring form means for receiving different sizes of cigars or cigarettes.

In assembling the device, the body is 20 slipped on the stem or bit 10 from the mouth-piece and thereof, until the shoulder or ring 16 abuts the shoulder 13 on the stem after which the spring 18 is inserted within the sleeve or cylindrical shaped body 15 by 25 coiling the spring and when the spring is fully inserted in the body the spring is released and the outermost convolution will seat against the shoulder 17 and the innermost convolution will seat against the flange or collar 12.

Thus at this point, it is to be noted that the spring forms a three-fold function, first, for the holding the body 15 in an extended cigar or cigarette receiving position; second, for 35 permitting the retracting of the body on the stem for ejecting a cigarette or cigar butt; and third, for holding the parts in an assembled position.

When it is desired to use the holder, the 40 cigar or cigarette is inserted within the body 15 into frictional contact with one or more convulsions of the spring. After the cigar or cigarette has been smoked, it is merely necessary to move the stem or bit and the 45 sleeve 15 toward one another and the cigar or cigarette butt will be automatically ejected from the holder.

Changes in details may be made without departing from the spirit or the scope of this 50 invention, but:-

What I claim as new is:

1. A cigar and cigarette holder comprising an elongated stem portion having a stop shoulder at its forward end, a cylindrical 55 body portion slidably mounted upon the stem having a stop shoulder on its inner end for engaging the stop shoulder on the stem, a stop shoulder on the outer end of the body portion of greater diameter than the shoulder on the stem, and an expansion coil spring arranged in the body seated against the shoulder on the outer end of the body portion and against the outer end of the stem whereby the body portion and stem portion 60 are held in assembled position relative to one 65

another and in a normally extended condition.

2. A cigar and cigarette holder comprising an elongated stem having a mouth-piece at its rear end and a stop shoulder at its forward end, a cylindrical body portion slidably mounted upon the stem having a shoulder on its inner end for engaging the shoulder on the outer end of the stem, the interior diameter of the shoulder on the body being 70 greater than the diameter of the mouth-piece, a stop shoulder on the outer end of the body of greater diameter than the diameter of the shoulder on the mouth-piece, and an expansion spring housed within said body engaging the shoulder on the outer end of the body and the outer end of the stem whereby the stem and body will be held in an assembled position relative to one another and normally 75 in an extended operative condition.

3. A cigar and cigarette holder comprising an elongated stem having a mouth-piece at its inner end and an annular stop shoulder at its outer end, a cylindrical body portion slidably mounted on the stem having a shoulder on its inner end engaging the shoulder on the outer end of the stem, a stop shoulder on the outer end of the body, and an expansion spring housed in said body engaging the outer end of the stem and the shoulder on the outer end of said body, said expansion spring being of the coil type and having the convulsions thereof lessening in diameter 80 toward the inner end thereof for receiving 85 cigars and cigarettes of different diameters.

In testimony whereof I affix my signature.
WAYNE FARRIS.
